STEERING WHEEL WRITING DESK

Robert W. Patterson, 1201 S. 3rd St., St. Charles, Ill.

Filed Jan. 10, 1964, Ser. No. 78,144

Term of patent 14 years

(Cl. D14—30)

FIG. 1 is a top plan view of a steering wheel writing desk embodying my new design;

FIG. 2 is a view of the top edge thereof;

FIG. 3 is a view of one side edge thereof;

FIG. 4 is a view of the bottom edge thereof;

FIG. 5 is a view of the other side edge thereof; and

FIG. 6 is a view of the bottom side thereof.

I claim:

The ornamental design for a steering wheel writing desk substantially as shown.
